Primary Examiner — Cynthia Ramirez*Assistant Examiner* — Xavier Marti-Santos(74) *Attorney, Agent, or Firm* — Tarolli, Sundheim, Covell & Tummino LLP(57) **CLAIM**

The ornamental design for an armchair, as shown and described.

DESCRIPTION

FIG. 1 is a front right perspective view of an armchair in accordance with one example embodiment of the present disclosure;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the figures are for the purpose of illustrating portions of the armchair and form no part of the claimed design.
